MARBLE SHOOTER

John O. Thompson, Box 133, Osage, Wyo.
Filed May 16, 1963, Ser. No. 280,863
6 Claims. (Cl. 124—10)

The present invention is generally concerned with toys, and more particularly relates to a novel marble shooting or propelling device.

Basically, it is an object of the instant invention to provide a marble shooter which can be conveniently manipulated so as to receive a single marble, and effect a forced projection of the marble.

In conjunction with the above object, it is also an object of the instant invention to provide a device which can be utilized when playing conventional marble games.

Likewise, it is an object of the instant invention to provide a device which can be easily manipulated by a child.

Further, it is an object of the instant invention to provide a marble shooting or projecting device wherein a substantial degree of accuracy is provided.

The above objects are achieved by the provision of a marble shooter which basically consists of a pair of elongated superimposed members having facing surfaces, each surface including a raised central portion for fulcrum engagement with each other. A resilient or elastic band is engaged about the members toward one side of the raised central portions so as to bias the members in opposite directions about the fulcrum and thereby maintain one pair of corresponding ends of the members adjacent each other while the other pair of ends diverge outwardly from the fulcrum forming raised center portions. The facing surfaces of the adjacent ends include longitudinally extending relatively shallow central loading grooves of a size so as to receive the periphery of a marble and guide the marble therein. The inner surfaces of the diverging ends of the members are provided with substantially deeper centrally located longitudinally extending guide grooves which terminate beyond the fulcrum forming raised central portions in an arcuate shoulder forming seat. This seat receives the marble inserted through the opened normally adjacent ends with the marble being projected forcibly outward along the guide grooves by a compressing of the opened normally adjacent ends so as to fulcrum the members about the marble and open the normally divergent ends, this fulcruming movement of the members, in conjunction with the compressive force exerted by the elastic band, effecting the projection.

These together with other objects and advantages which will become subsequently apparent reside in the details of construction and operation as more fully hereinabove described and claimed, reference being had to the accompanying drawings forming a part hereof, wherein like numerals refer to like parts throughout, and in which:

FIGURE 1 is a perspective view of the marble shooter comprising the instant invention;

FIGURE 2 is an exploded perspective view of the various elements of the shooter;

FIGURE 3 is an elevational view of the resilient or elastic band;

FIGURE 4 is a cross-sectional view taken substantially upon the plane passing along line 4—4 of FIGURE 3;

FIGURE 5 is a cross-sectional view taken substantially on a plane passing along the line 5—5 of FIGURE 2;

FIGURES 6, 7 and 8 are cross-sectional views taken along the corresponding section lines in FIGURE 5;

FIGURE 9 is a longitudinal cross-sectional view through the marble shooter; and

FIGURES 10, 11 and 12 illustrate the various steps in loading and firing the marble shooter.

2

Referring now more specifically to the drawings, reference numeral 20 is used to generally designate the device comprising the instant invention. This device 20 basically includes a pair of elongated normally superimposed members 22 and a resilient or elastic band 24 resiliently clamping the members 22 together.

Each of the elongated members 22, which incidentally may be formed of any suitable rigid material such as wood, plastic or metal, includes a flat outer surface 26 and an angular inner or facing surface 28. The facing surface 28 of each of the members 22 increases smoothly in height from the outer ends thereof to a raised central portion 30 forming, as shall be presently apparent, a centrally located fulcruming point.

The resilient band 24 is engaged about the members 22 to one side of the superimposed raised central portions 30, this side being herein designated as the loading side or end. Incidentally, it will be noted that the outer surface 26 of each of the members 22 is provided with a transversely extending retaining groove 32 for retaining the resilient band 24 in its proper location relative to the members 22, and at the same time acting so as to also retain the proper relationship between the members 22.

As will be appreciated, the band 24, in this position, biases the loading end of the members 22 in opposite directions about the fulcruming points 30 so as to orientate these loading ends adjacent each other while the opposite sides or ends, which will be herein designated as the projecting ends, are orientated outwardly in divergent relationship to each other.

Each of the members 22 includes, in the facing surface 28 thereof, a centrally located relatively deep guiding groove 34 extending longitudinally in from the extreme end thereof to a shoulder forming arcuate seat 36 located beyond the raised central portion 30 and in the general vicinity of the band 24. In addition, each of the members 22 includes a longitudinally extending loading groove 38 centrally along the loading end thereof, this loading groove 38 being shallow as compared to the corresponding guide groove, and communicated with this groove with which it is longitudinally aligned. Incidentally, it will of course be appreciated that both the guide channels and the loading channels are formed so as to generally conform to the periphery of the marble, portions of which will be received within the corresponding channels in the use of the device as shall be explained presently. Further, it will be noted that the fulcrum forming raised centrally located portions 30 in fact consist of, in regard to each member 22, a pair of raised portions defined by the central guide groove 34.

Finally, each of the members 22 is provided, in the outer surface 26 thereof, with a longitudinally extending centrally located sighting groove 40 for use in an obvious manner for aiming the shooter 20.

Referring now specifically to FIGURES 9—12, the use of the device will be explained. Initially, the loading ends of the members 22 are maintained adjacent or in contact with each other with the projecting or shooting ends in diverging relation to each other. The loading ends are separated from each other, as for example by compressing the projecting ends toward each other, and a marble is loaded therein utilizing the loading grooves 38. With reference to FIGURE 11, it will be noted that the marble is forced into seating engagement with the shoulders 36, thereby resiliently biasing apart the centrally located fulcruming points 30. With regard to this specific position, it will be noted that the resilient band 24 is located slightly forward of the vertical diametric plane of the marble so as to maintain the converging relationship of the normally divergent projecting ends when the marble itself is used as a fulcruming

means, thereby maintaining the marble against the seat forming shoulders 36. The final step involves the compressing of the loading ends toward each other, thereby pivoting the members 22 about the marble so as to spread the projecting ends and project the marble therefrom by means of the diverging guide grooves 34 and the compressive force exerted by the resilient band 24 as it moves beyond the central vertical plane of the marble.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. A marble shooter comprising a pair of elongated superimposed members having fulcrum forming means adjacent the center thereof, resilient means biasing said members in opposite directions about said fulcrum forming means for retaining one end of one member adjacent an end of the other member with the other ends spaced apart, marble guide means on at least one of said members for guiding movement of a marble longitudinally between the members, said marble guide means including a shoulder for engaging a marble and preventing movement of the marble in one direction, said shoulder being disposed between the center of the member and the ends of said members normally retained in adjacent relation and facing the center of said members, whereby insertion of a marble between the adjacent ends of said members will pivot the adjacent ends apart, said shoulder receiving the marble and retaining it in place thereby retaining the normally adjacent ends of the members in spaced apart relation whereby subsequent movement of the normally adjacent ends of the members will cause fulcrumming thereof about the marble until the surfaces of the members diverge from the shoulder and marble to the other ends thereof for ejecting the marble therefrom.

2. The structure as defined in claim 1 wherein said fulcrum forming means also includes raised side edges on each of said members with the raised side edges engaging each other and forming a fulcrum axis but enabling the 45 members to move apart.

3. The structure as defined in claim 2 wherein said resilient means includes a resilient band encircling said members adjacent the raised portions but between the raised portions and the normally adjacent ends for retaining the normally adjacent ends normally adjacent each other and enabling the raised portions forming the fulcrum axis to move apart to enable passage of a marble therebetween.

4. The structure as defined in claim 3 wherein said marble guide means also includes a channel in each of the end members generally of cross-sectional configuration to receive a portion of the periphery of the marble, the channel from the shoulder to the normally spaced apart ends of said members being deeper than the channel from the shoulder to the normally adjacent ends thus forming the shoulder at the juncture between the channels.

5. The structure as defined in claim 4 wherein the outer surface of each longitudinal member is provided with a longitudinal guide line thereon for use in aiming the marble shooter.

6. A marble shooter comprising a pair of elongated members having facing surfaces provided with a raised central portion for fulcrum engagement with each other and being disengageable from each other, a resilient means retaining the raised portions in fulcrum engagement with each other but enabling them to be moved apart, a channel extending longitudinally on each face and extending from one end of the members to a point beyond the fulcrum with the channels being spaced apart a distance less than the diameter of the marble whereby a marble disposed in said channel at the inner end thereof will be projected therefrom when the channel surfaces are orientated in diverging relationship to each other with marble holding the fulcrum points apart whereby the resiliency of the resilient means will combine with the diverging surfaces of the channels to project the marble.
